HOUSING FOR COMBINED SOUND AND MOTION-PICTURE PROJECTORS

Philip S. Malickson, Bala, Pa.

Application September 29, 1934, Serial No. 746,089

1 Claim. (Cl. 88—16.2)

My invention relates to photo-acoustic cinematographic unit, and relates more particularly to the housing of the unit.

It is an object of my invention to produce a 5 housing for a combined picture and sound projector that lends itself readily to transportation by hand, contains a minimum of parts, and the volume of which is reduced to a minimum.

Another object of my invention is to electrically 10 shield the entire unit by a metallic casing to prevent the transmission of feedback noises or electrical disturbances to the sound reproducing circuits located outside of the casing which noises or disturbances may come from the power circuits 15 operating the various mechanisms and the light source in the casing.

Another object of my invention is to provide a substantially fire-proof housing.

Another object of my invention is to make a 20 sturdy housing that is substantially sound-proof and vibrationless.

Another object of my invention is to equip the casing with means for adjusting its vertical position in a stable manner.

25 A still further object of my invention is to construct a housing that is symmetrically proportioned in order to be pleasing in appearance.

Other objects of my invention are to provide an improved device of the character described, which 30 is easily and economically produced, that is sturdy in construction, and which has a maximum efficiency and accuracy in operation.

With the above and related objects in view, my invention consists in the following details of construction and combination of parts, as will be more fully understood from the following description, when read in conjunction with the accompanying drawings; in which:

Fig. 1 is an assembled perspective view of the 40 housing and the reel supporting arms.

Fig. 2 is a side elevational view of the fixed side plate of the casing.

Fig. 3 is a sectional view taken on the line 3—3 of Fig. 2.

45 Fig. 4 is a perspective view of the elevating bracket.

Fig. 5 is a side elevational view of the movable door for the housing.

Fig. 6 is a perspective view of the movable door.

50 Fig. 7 is a sectional view taken on the line 7—7 of Fig. 6; showing its cooperating wall in dotted lines.

Fig. 8 is a sectional view taken on the line 8—8 of Fig. 6, showing its cooperating wall in dotted 55 lines.

Fig. 9 is a side elevational view of the door side of the housing.

Fig. 10 is a rear elevational view of the housing.

Referring in detail to the drawings, in Fig. 1, 9 and 10 is shown a casing, generally designated 5 as A, and comprised of metal, such as cast aluminum. Since the projection mechanism, described in my copending patent application Serial No. 481 filed January 5, 1935, is of considerable weight the housing must possess the requisite strength and, also, must withstand the strain imposed without the various elements moving from their original position. The housing A is comprised of a substantially rectangular base 10 of relatively thin metal. Integrally formed 15 with the base 10 at its transverse edges 12, 14 are vertically extending parallel front and back walls 16, 18 respectively.

From the upper edge 18 of the front wall is an angularly extending wall 20 which is joined at 20 its edge 22 by a ceiling 24. The ceiling or top wall 24 extends parallel to and over the base 10, and the end 26 of the ceiling is joined to the rear wall 18 by an angularly extending wall 28.

To form a substantially enclosed chamber for 25 the projecting apparatus a side wall 30, Figs. 2 and 3, is provided to close one side of the chamber. The side wall or side plate, generally designated as B, is comprised of a substantially thin

30 flat plate, the plate is substantially rectangular as viewed from the side, except that its upper corners are diagonally cut; the plate is so formed in order that the plate will join the side edges of the base, the ceiling, the side and front walls, and angularly disposed walls 20 and 28. A continuous 35 bead 32 is mounted upon the interiorly positioned portion of the side plate or side wall 30; and the bead is located close to the peripheral edges of the side plate. The bead 32 is adapted

40 to extend interiorly of the housing and the transversely extending members of the housing are adapted to be limited in one direction of movement by the bead. As illustrated in Fig. 3 the ceiling 24 and the base 10 shown in dotted lines are adapted to engage the bead. The bead pre- 45

vents the buckling or folding of the housing when the housing together with its coordinate members is carried. A plurality of openings 34 located between the bead and the outer edge permits the body of bolts to be passed therethrough 50

in order that the plate may be suitably attached in position. A plurality of openings 36 are for air to pass through the side plate into the interior of the housing.

A hinged door, generally designated as C, pro- 55

vides the closure for the second side of the chamber. The door C has a main body portion 38 hinged at its vertically extending fold 40. Folds, hereinafter further described, are formed integrally with and extend perpendicular to the main body portion 38, which is substantially a flat plate. The perpendicularly extended folds embrace a portion of the walls 16, 18, the angularly extending walls 20, 28 and the ceiling 24. Thus, the folds serve as additional braces to prevent the buckling or expanding of various portions of the outer housing.

A hinge 41 is attached to the rear wall 16 and the rear vertically extending fold so that the door 15 swings about a vertically positioned axis.

In order to provide a suitable support and brace to prevent the buckling or the expanding of the various portions of the transverse members of the housing, the folds have their outer 20 ends formed to pass exteriorly and interiorly adjacent the side edges of the various transverse members comprising the housing. The upper horizontally extending fold 42 well shown in Figs. 6 and 8, has its upper surface 43 in the same 25 plane but its lower surfaces 44, 45 are offset from one another, a surface 46 is substantially perpendicular to the surfaces 44, 45 and forms a ledge against which the edge of the ceiling 24 rests. The surface 45 of the fold as viewed in 30 Fig. 8 rests upon the upper surface ceiling 24 so that the surface 45 is exteriorly positioned with respect to the chamber formed by the housing.

The front vertically extending fold 48, well illustrated in Figs. 5, 6, and 7 has its interior 35 surface 49 extending in the same plane and its outer surfaces 50, 51 offset from one another. A surface 52 joins the edges of the surfaces 50, 51 and the surface 52 serves as a ledge against which an edge of the front wall 16 engages. The 40 surface 50 is substantially flush with the exterior surface of the front wall 16.

The bottom fold, the rear vertically extending fold 40 and the angularly disposed folds are constructed similarly to the vertically extending 45 front fold 48.

With the door C in closed position and the side plate B attached to the housing it will readily be seen that when the handle or grip, generally designated as D, is grasped to carry the casing 50 an upward force is placed upon the ceiling 24. The edge of the ceiling 24 engages the surface 45 of the fold 42, thus preventing a bulging of the top of the casing.

The weight of the mechanism inside the housing is the equivalent of a downwardly extending force upon the base 10 of the housing. Such force tends to cause the central portion of the base 10 to drop which if unsupported would result in the walls 16 and 18 being drawn together. However, since the interior portion of the folds 40 and 48 oppose the inward movement of the walls 16 and 18, respectively, it will be readily seen that the only downward movement of the base would result from the elongation of the base itself created by the force imposed thereon. Since the metal used as a base possesses the requisite tensile strength, there is substantially no movement of base. It is, also, to be remembered, at this time that the bead on the side place B is engaged to off-set any tendency of the walls of the casing to converge at their lower extremities; and the bead, also, forms a rest both for the ceiling and the base of the casing in order 75 that the housing will be able to withstand the

various strains and stresses which may be imposed thereon.

A rectangular opening 54 having a transparent body therein is suitably positioned in the door C in order that the film passing the film moving mechanism may be viewed by the person operating the projector during the time that the door is closed.

An opening 56 adjacent the rear portion of the ceiling 24 enables a hood 58 for a source of 10 light to protrude therethrough.

A slit 60 extends from one side of the ceiling 24, to a larger opening adjacent the handle D wherein there are a plurality of rollers 62 and 64. The rollers 62 and 64 are under cut on their 15 curved bounding surface adjacent the handle D. The purpose of under-cutting the rollers is to save wear on the film emulsion of the film sound track since the scraping of the sound track will cause undue and extraneous noises to be emitted 20 from the loud speaker.

The supply reel support 66 is detachably mounted upon the upper surface of the ceiling 24 adjacent the edge 22 by means of screws 68 and 70 passing through a flange of the support 66. 25 The holding screws are of the type that may be easily removed in order to enable the support 66 to be detached or attached to the housing as the case may be. The support 66 and the rollers 62, 64 are positioned so that film designated as 30 F from a supply reel 72, schematically shown by dotted lines, will pass from the reel past the rollers with a minimum degree of bending.

A circular opening 74 is located on the front wall 16 through which opening rays of light 35 carrying an image may pass.

A horizontally positioned slit 76 extends from an edge of the front wall to an aperture wherein rollers 78, 80 are located, the rollers are positioned parallel to one another in a horizontal 40 plane. The film F is guided on the rollers 78, 80 to a film take-up reel, generally designated as G, which reel is schematically shown. Each set of rollers 62, 64, and 78, 80 are in substantially the same vertical plane in order that the film shall 45 move in the same vertical plane. It is to be observed at this time that the slits 60 and 76 enable the easy threading of the film into and from the housing. Also the location of the supply and take-up reels is such that they will not cause 50 undue bending of the film; for it is well known that the film, and the maintenance of the film is expensive and that the machine should have no deleterious effect on the film.

An aperture 82 in the front wall 16 permits the 55 passage of an electrical plug whereby the leads from the photo-electrical cell may be attached to the amplifying circuit and a plug from the power circuit may be inserted through an aperture 84 to connect it to the exciter lamp. A 60 take-up reel support arm is adjustably mounted on the casing H. The adjustable take-up reel bracket is described in detail in my co-pending application, Serial No. 746,088, filed September 29, 1934. 85

In order to vertically adjust the complete housing I mount a rectangular strip, generally designated as J, upon the central lowermost portion of the front wall 16. The strip has parallel side walls 94A and 96A, and a front wall wherein 70 a threaded opening 98 is located.

A movable elevating device, generally designated as K, has a main body portion 99 and a central slot 92 therein. The portion of metal adjacent the rear of the slot 92 is milled so that 75

its parallel vertically extending sides 94 and 96 are complementary to the parallel vertically extending sides 94A and 96A of the strip J. The threaded opening 98 in the strip J is adapted 5 to receive and retain an end of the thumb screw 100. The screw 100 is adapted to pass through the slot 92 and retains the elevating device K securely against the strip J. In operative position, the sides 94, 94A and 96, 96A are in engagement, thus no tilting of the housing will occur 10 relative to a longitudinally vertically extending plane. The elevating device K has legs 102, 104 at each end in order that there will be at least a two-point support at the front end of the housing. By unloosening the thumb screw 100 and moving the elevating device downwardly and then tightening the thumb screw, the front portion 15 of the housing may be elevated in order that the rays of light passing through the aperture 74 may be raised. The front portion of the housing may be lowered by reversing the above procedure. The vertical movement of the front of the housing is limited only by the length of the slot 92.

Upon the bottom of the base 10 adjacent the 20 rear wall 18 is a plurality of legs 106 which legs are preferably comprised of rubber. The legs are positioned so that the housing will remain stable when the elevating device K is either in raised or in lowered position.

Placed adjacent each of the side walls B and C 25 are asbestos boards which deaden extraneous noises.

Mounted upon the front of the door and the front wall of the housing are a plurality of locks, 30 each of which may easily be opened by raising a

latching lever. A knob on the door enables the door to be easily opened.

Although my invention has been described in considerable detail, such description is intended to be illustrative rather than limiting since the invention may be variously embodied and the scope of the invention is to be determined as claimed. 5

I claim as my invention:—

A portable housing for a combined sound and motion picture projector comprising a flat metallic base; front and rear parallel vertically extending walls joining the ends of the base; a flat wall inclined towards the center of the vertically extending central axis of the housing; and a flat 15 ceiling parallel to the base and joining the upper end of each inclined wall; the edges of the complementary base, front and rear walls, the inclined walls and the ceiling joined to form an integral structure; a removable flat side plate having a 20 bead thereon whereby the inside edges of the walls will abut against the bead in order to support the side edges of the said base, front and rear walls, inclined walls and the base; a pivoted flat side door for the second side of said housing, said 25 side door having a flange laterally extending from its edges, and a fold on the upper horizontal edge of the flange adapted to overlap a portion of the outer surface of the ceiling when the door is closed, and a plurality of folds extending from 30 the bottom and side flanges adapted to overlap the interior portion of said base and side walls; and a handle on the outer portion of the ceiling.

PHILIP S. MALICKSON. 35
